GAME BOARD

Michael Vawryk, 19 Evergreen Drive,
Lyndora, Pa. 16045

Filed Nov. 14, 1967, Ser. No. 9,397

Term of patent 14 years

(Cl. D34—5)

The figure is a top plan view of a game board, showing my new design.

The board is of conventional thickness.

I claim:

The ornamental design for a game board, as shown and described.
